RING BINDER CONSTRUCTION

John Schade, Holyoke, Mass., assignor to National Blank Book Company, Holyoke, Mass., a corporation of Massachusetts

Application October 28, 1943, Serial No. 507,984

1 Claim. (Cl. 129—24)

This invention relates to an improvement in ring binders of the type employing a wire arch frame in the toggle mechanism. This type has the advantages of a low manufacturing cost and the need for but a comparatively small amount of metal. It has the disadvantages that it is a type primarily adapted for but two rings in the binder, and the ways heretofore proposed in the art for adding more rings lead into difficulties.

The purpose of my invention is to provide a new construction in which the advantages of the wire arch frame construction for the toggle mechanism may be retained and more rings than two put in the structure in a very simple manner with the advantages I will point out.

According to my invention I employ as a foundation a usual and simple form of wire arch frame. This consists of two wires having their ends bent into complementary ring halves, two mating toggle arches adjacent each end ring, and having a tendency to bow outwardly between the toggle arches when assembled in a spring plate. To this foundation I add as many additional rings as desired, between the end rings, but without any additional toggle acting parts adjacent the additional rings. The way I do this is shown in the drawing.

Fig. 1 is a top plan view of the binder;

Fig. 2 is a bottom plan view of the binder;

Fig. 3 is a section taken on line 3—3 of Fig. 1;

Fig. 4 is a view similar to Fig. 3 but showing the rings in open position;

Fig. 5 is a view on line 5—5 of Fig. 1; and

Fig. 6 is a perspective view of a part essential to the combination in the practice of my invention.

As shown by the drawing, my structure consists of a spring cover plate 1 bent down at 2 to form pockets for wire members 3. The wire members 3 are bent to form toggle connections at 4 and ring halves at 5. The ring halves extend through openings 6 punched in the cover plate 1, and the toggle connections 4 lie on about the same plane as the bottom end of the cover plate sides 11 or a little above this plane when the rings are in closed position and abut the stops 7, punched down from the coverplate 1, when the rings are in the open position as in Fig. 4. The stops 7 limit the opening of the rings to that amount considered necessary for desired operation of the binder. The wires 3, between the toggle connections 4, lie in straight pockets of the spring plate 1 formed by the bent down sides 2. In this position the wires 3 are held substantially straight. The wires 3 have a tendency to bow outwardly.

This tendency is counteracted by the straight sides 2. Such tendency to bow outwardly is given to wires 3 by giving them an outward but slight permanent bend which is resiliently straightened out when assembled in the spring plate pockets which are straight as shown. The result is that wires 3 have a strong tendency to lie straight and firmly engaged in the pockets of the spring plate. This gives the foundation structure of the prior art.

To this foundation structure I add one or more additional rings by the structure indicated in Fig. 5. This consists for each ring added of the two ring segments 8. Their lower ends are welded as at 9 or otherwise fastened to adjacent wires 3. They extend up through the spring cover plate for their upper ends to match as the other rings do. With such added ring segments on wires 3, the wire arch frame is assembled with the spring plate with substantially the same convenience as if the frame had only two instead of more than two rings. The only difference is that the added ring segments need to be threaded through the holes provided for them in the spring plate. The frame is flexible and the plate is sufficiently resilient for fast and easy assembly. In the assembly there is no cross connection between the wires 3 between their ends. Everything is loose until the toggle joints or connections 4 at opposite ends snap together.

The arrangement described is one which makes the assembly quick and easy. But after the assembly, there is a difficulty with the structure. While the tendency of wires 3 between toggles to bow outwardly will hold ring segments 8 so as to close properly under some conditions, they will not hold them properly closed or in position to properly close under other conditions of use. For example they will close properly and stay closed when desired, as in Fig. 5 except under these conditions. If any force is applied to one of the ring segments 8, as by the weight of a book or striking against the desk, the ring segments will get out of closed positions at their end. One is frequently sprung down and caught under the other ring segment. This is of course a bad condition as the sheets will be torn if turned over without noticing the condition of that ring. A main purpose of my invention is to avoid this difficulty while retaining all the advantages of the foundation structure.

To avoid such difficulty I provide the part shown in Fig. 6 by itself and shown in Figs. 2 and 5 as part of the combination. It consists of a piece of thin sheet metal. It is channel

shaped to give stiffness. The flat top 10 and downwardly turned sides 14 make a stiff piece adapted however for snap on assembly. Its inwardly curved slots 13 are dimensioned to receive wires 3 as seen in Fig. 5. When this part of Fig. 6 is merely pressed down by hand into the position of Fig. 2 and Fig. 5, it will snap into position. The dimensions are such that the spring plate 1 with its bent down sides 2 help the snapping on action. And the arrangement is such that the piece of Fig. 6, snapped into the position of Fig. 5, will hold the wires 3 from being sprung downwardly. This will prevent the upper ends of ring segments 8 from being sprung apart for one to get under the other and make a misfit. The flat side 10 is preferably arranged in about the same plane as the lower edges 11 of bent down parts 2. Then when the assembly is fastened to the back panel of a binder there is a stop to prevent the downward movement at the plane of the flat side 10. Of course this side is preferably shaped to fit the transverse form of the back panel. When the ring segments 8 are opened the arch of spring plate 1 is flattened. The top edges of sides 14 then contact the underside of the spring plate. A stop is thus provided against too much ring opening action. The stop in this respect cooperates with the stop function of depressions 7 for the end ring action. It will be seen that the inner ends of segments 8 lie within the cavity formed by sides 10 and 14. This arrangement holds the piece of Fig. 6 from shifting lengthwise of the spring plate. It will now be seen that my improved structure is finished when I snap into place a channeled-shaped strut in the cross plane of each pair of ring segments as seen in Fig. 2. I have retained all the

advantages of the prior art structure in this way. It can be made exactly as before with all the advantages of economy of parts and assembly, then, by adding the separately made part of Fig. 6 by merely snapping it in place, a disadvantage of the prior art structure is avoided and the new combination works better.

Having disclosed my invention, I claim:

In a ring binder construction of the wire arch toggle frame type providing for end rings assembled in a spring cover plate with down turned edges holding the side wires, their toggle arrangements and their two end ring constructions in operative relation, the combination of at least one additional ring construction formed by complementary ring prongs each with its lower end adjacent and made fast to one of the side wires for its only connection to turn therewith and a support for the action of said additional ring construction, the said support comprising a single piece of thin sheet metal having a base portion to span the distance between the downturned edges of the cover plate, with upturned sides providing a narrow trough in which the lower ends of the said ring prongs may lie, and recesses in the side walls to engage and receive the side wires, and top edges generally following the transverse curve of the cover plate, said support being adapted to snap into position with said wall recesses engaged by the side wires with said base portion in position as a transverse shelf underlying both wires and the top edges of the side walls slightly spaced from the cover plate when the rings are closed and permit them to open as the toggle wires spread the cover plate in the toggle action.

JOHN SCHADE.
